UNITED STATES PATENT OFFICE

109,800

DESIGN FOR A FINGER RING

Alfred R. Foss, New York, N. Y.

Application March 9, 1938, Serial No. 75,695

Term of patent 3½ years

To all whom it may concern:

Be it known that I, Alfred R. Foss, a citizen of the United States of America, residing at city, county, and State of New York, have invented a new, original, and ornamental Design for Finger Rings, of which the following is a specification, reference being had to the accompanying drawing, forming part thereof.

The figure is a perspective view of a finger ring showing my new design.

I claim:

The ornamental design for a finger ring, as shown.

ALFRED R. FOSS.
